Webster & Co.,
ATTORNEYS.

UNITED STATES PATENT OFFICE.

WILLIAM L. CRONIN, OF SPRINGFIELD, MASSACHUSETTS.

BOILER-FLUE BLOWER.

1,116,873.

Specification of Letters Patent. Patented Nov. 10, 1914.

Application filed March 10, 1914. Serial No. 823,239.

To all whom it may concern:

Be it known that I, WILLIAM L. CRONIN, citizen of the United States of America, residing at Springfield, in the county of 5 Hampden and State of Massachusetts, have invented a new and useful Boiler-Flue Blower, of which the following is a specification.

My invention relates to improvements in 10 front-end blowers for flue boilers of the stationary type, whereby the operator can direct the cleaning jets of steam longitudinally of the flues without opening the smoke doors, and without inconvenience to himself, 15 and said invention consists of a counter-weighted rotatable jet tube or arm connected with a steam chest which is supported from a cross bar, all as hereinafter set forth.

The object of my invention is to provide 20 for a boiler a simple, convenient, and efficient flue blower or cleaner, that may receive its supply of steam from one side of or from above said boiler, at the front end of the same, and is not attached to any door or 25 other movable part, which attachment is an obvious disadvantage.

A further object is to provide means for 30 readily placing my blower or cleaner in position and removing the same when necessary, all without taking down, dismantling, or otherwise disturbing the usual or regular and ordinary boiler parts and members at the front end.

Other objects and advantages will appear 35 in the course of the following description.

I attain the objects and secure the advantages of my invention by the means illustrated in the accompanying drawings, in which—

40 Figure 1 is a central longitudinal vertical section through a boiler or the front end portion thereof, showing the application thereto of a practical embodiment of my blower, the blower arm standing vertically; 45 Fig. 2, a front end elevation of said boiler, with parts broken out to disclose said blower, said arm in this view being turned out of the vertical position which it occupies in the preceding view; Fig. 3, an enlarged 50 side elevation and partial section of the blower; Fig. 4, a cross-section, taken on lines 4—4, looking in the direction of the associated arrow, in Fig. 3, and, Fig. 5, an enlarged top plan of one terminal of the supporting bar for the blower, showing how the 55 same is secured to the boiler.

Similar numerals refer to similar parts throughout the several views.

Referring to the drawings, it will be seen that I have there shown a boiler shell 1 provided with a front head 2 and tubular flues 3, and arranged in an ordinary brick setting 5 and plate setting 6. The shell 1 projects at the forward terminal to form a dry sheet 7. The latter has a ring 8 in its front end, 60 such ring being angular in cross-section. Smoke doors 9 and 10, of usual construction, are hinged to the vertical part or flange 11 of the ring 7. These parts and members, together with a line of pipes which constitutes a steam-supply conduit 12, a valve 13 and operating stem 14, and a drip pipe or pipes 15 and a drip valve 16, are all old and well known.

The conduit 12, in the present case, enters 75 the dry sheet 7 from or at one side, extends over to the vertical center, but well above the horizontal center, of said dry sheet, the planes of such centers being lengthwise of the boiler, and at such vertical center turns 80 directly downward. This inner vertical part of the conduit 12 is located just behind the vertical plane of the inner edge of the ring 8.

Extending across the front end of the dry 85 sheet, at a height sufficient to avoid obstructing or interfering with the flues 3 at their front ends, is a bar 17. Each end of the bar 17 is bolted at 18 to the ring flange 10, against the inner face thereof. If necessary 90 the bar 17 is inwardly offset adjacent to the ends thereof, such necessity arising when the construction of the blower part directly attached to said bar would prevent said part from being placed in position, owing to the 95 close proximity of the central overlapping or meeting edge portions of the doors 9 and 10. In Fig. 1, the central vertical flange of the door 9 is shown in section at 19.

The blower comprises a steam chest 20, a 100 collar-yoke 21 within said chest, a jet tube or arm 22 connected with said collar-yoke at one end and an operating rod 23 connected with said yoke at the other end, and a counterweight 24 for said arm. A bracket 105 arm 25 rises from the front end of the steam chest 20, and said arm is bolted at 26 to the cross bar 17, against the back thereof in the center. In this manner and by this means the blower is securely fastened in place and 110 located most advantageously relative to the flues 3, that is to say, the arm 22 is so situ-

ated that it can be rotated on the collar-yoke 21 as an axis in front of said flues. The aforesaid vertical part of the conduit 12 that is within the dry sheet 7 opens at its base into the top of the steam chest 20, the former being tapped into the latter. Steam under pressure is thus admitted to the chest 20, when the valve 18 is opened, and passes into the arm 22, through a short length of pipe 27 and an elbow 28, to escape in jets from said arm through a series of nipples 29 with which said arm is provided on the side next to the flues 3. The pipe 27 has one end tapped into the inner or rear end of the collar-yoke 21 and the other end tapped into the elbow 28. One end of the arm 22 is tapped into the elbow 28 and the other end of said arm is closed by means of a cap 30. The nipples 29 are spaced to correspond with the spacing of the flues 3, and by preference said nipples have a conical or other form that produces larger openings at their inner ends than at their outer ends, so as to increase the force of the steam at the points of exit. By increasing the steam pressure in this manner more powerful jets are discharged into the flues and the cleaning effect is enhanced accordingly. Conical openings through the nipples 29 are clearly shown at 31, in Fig. 3.

The inner end of the steam chest 20, through which the pipe 27 extends, is closed by means of a plate 32, which fits around said pipe and is bolted, as indicated at 33, to said chest. Packing material 34 is inserted in the chest 20, between the plate 32 and the adjacent end of the collar-yoke 21. The pressure from the steam in its passage through the chest 20 into the pipe 27 tends to force the collar-yoke tightly against the packing 34.

The rod 23 has its inner end rigidly attached to the outer or front end of the collar-yoke 21, and is provided at its outer end 45 with a handle 35. The chest 20 is provided in the front end through which the rod 23 passes with a stuffing-box 36. The rod 23 extends forwardly beyond the front of the doors 9 and 10, the meeting-edge portions 50 of said doors being perforated to admit of the passage of said rod. It is by means of this rod, rotated from the outside of the boiler and its settings, that the arm 22 is operated, said arm being turned in either 55 direction, with the elbow 28, the pipe 27, and the collar-yoke 21, by said rod. The rear end of the collar-yoke 21 constitutes what may be termed a trunnion for the arm 22, such end or trunnion being journaled in 60 a bearing 37 provided for it in the back part of the chest 20 and forming part of said chest.

The object of the counterweight 24 is to balance the arm 22 and so to facilitate and 65 render easier the act of turning said arm by

means of the rod 23. The counterweight 24 is, therefore, mounted on a rod 38 which projects from the elbow 28 in line with the longitudinal center of the arm 22. Preferably the counterweight is mounted for adjustment on the rod 38, and to this end a set-screw or bolt 39 is provided, the latter being tapped into said counterweight and extending through into contact with said rod. 75

In operation, steam is injected through the conduit 12, the chest 20, the pipe 27, the elbow 28, and the arm 22 and nipples 29, into the ends of adjacent flues 3, and by proper manipulation of the rod 23 and said arm, through the medium of intervening parts and members, said nipples are brought into operative position relative to different sets of said flues, with the result that the jets are directed through the several flues 85 without inconvenience or danger to the operator.

Obviously, changes in details of construction may be made without departing from the spirit of my invention, and I do not wish to limit myself to any particular form or arrangement of parts other than the scope of my claims renders necessary. 90

What I claim as my invention, and desire to secure by Letters Patent, is— 95

1. The combination with a flue boiler and the front end inclosing members therefor, including the smoke doors, and a steam-supply conduit entering the space between said boiler and said inclosing members, at 100 right angles to the axis of said boiler, of a member connected with said conduit, means, separate from and independent of said doors, to support said last-mentioned member, a jet-pipe connected with said last-mentioned member and adapted to be revolved in a plane substantially parallel with the adjacent boiler end, and exterior means for revolving said jet-pipe. 105

2. The combination with a flue boiler and the front end inclosing members therefor, a steam-supply conduit entering the space between said boiler and said inclosing members, at right angles to the axis of said boiler, and a supporting member attached to fixed portions of said inclosing members, of a member connected with said conduit and attached to said supporting member, a jet-pipe connected with said member which is connected with said conduit, and adapted to 110 be revolved in a plane substantially parallel with the adjacent boiler end, and exterior means for revolving said jet-pipe. 115

3. The combination with a flue boiler and the front end inclosing members therefor, a steam-supply conduit entering the space between said boiler and said inclosing members, and at right angles to the axis of said boiler, a bar attached to said members, of a member connected with said conduit and 120

supported by said bar, a jet-pipe connected with said last-mentioned member and adapted to be revolved in a plane substantially parallel with the adjacent boiler end, 5 and exterior means for revolving said jet-pipe.

4. The combination with a flue boiler and dry-sheet, a steam-supply conduit entering said dry sheet behind the front end thereof, 10 and a cross bar supported within said dry sheet, of a member connected with said conduit and attached to said bar, a jet-pipe connected with said last-mentioned member and adapted to be revolved in a plane substan- 15 tially parallel with the adjacent boiler end, and exterior means for revolving said jet-pipe.

5. The combination with a flue boiler and front end members, and a steam-supply conduit, of a member connected with said conduit, means to support said last-mentioned member, a hollow arm connected with said last-mentioned member, said arm being provided with nipples having openings therein 20 which are constricted at their outer ends, 25 and exterior means to revolve said arm, the movement of said arm being in a plane sub-

stantially parallel with the plane of the adjacent boiler end.

6. A boiler flue blower comprising a steam 30 chest, a collar-yoke journaled in said chest, a pipe rigidly attached to said collar-yoke at one end and extending out of said chest, an elbow on the outer end of said pipe, a jet-pipe connected with said elbow, a counterweight mounted on said elbow, and a rod 35 rigidly attached to said collar-yoke at the other end and extending out of said chest.

7. The combination with a flue boiler having a dry-sheet, a steam-supply conduit 40 entering said dry-sheet back of the front end thereof, and a bar secured to said dry-sheet, of a steam chest having an arm, means to secure said arm to said bar, a collar-yoke 45 journaled in said chest, a jet-pipe connected with said collar-yoke and adapted to be revolved in a plane substantially parallel with the adjacent boiler end, and an operating rod for said collar-yoke.
